C Robert Turner, Cincinnati, Ohio, assignor to Nutone,
Inc., Cincinnati, Ohio, a corporation of Delaware

Filed Dec. 20, 1962, Ser. No. 72,909

Term of patent 14 years

(Cl. D81—25)

FIGURE 1 is a perspective view showing the front and a side of a combined range and hood unit showing my new design.

FIGURE 2 is a front perspective view thereof.

FIGURE 3 is a side elevational view thereof.

FIGURE 4 is a rear elevational view thereof.

FIGURE 5 is a top plan view thereof.

FIGURE 6 is a front elevational view of the control panel thereof which is shown in enlarged scale and separate from the unit for convenience of illustration.

The dominant features of the design reside in those portions shown in full lines.

I claim:

The ornamental design for a combined range and hood unit, substantially as shown and described.
